US0D1091228S

(12) **United States Design Patent** (10) **Patent No.:** **US D1,091,228 S**
(45) **Date of Patent:** **** Sep. 2, 2025**

(54) **MUG LID CONNECTOR**

(71) Applicant: **Yongkang Jingda International Trade Co., Ltd.**, Jinhua (CN)

(72) Inventor: **Yali Ge**, Xianning (CN)

(73) Assignee: **Yongkang Jingda International Trade Co., Ltd.**, Jinhua (CN)

(**) Term: **15 Years**

(21) Appl. No.: **29/992,760**

(22) Filed: **Mar. 11, 2025**

(51) LOC (15) Cl. **07-02**

(52) U.S. Cl.

USPC **D7/392**
